LUIS G. ABOGADO, OF MEXICO, MEXICO.

PROCESS OF STERILIZING LIQUIDS.

1,382,159.

Specification of Letters Patent. Patented June 21, 1921.

Application filed June 4, 1919. Serial No. 301,773.

To all whom it may concern:

Be it known that I, LUIS G. ABOGADO, a citizen of Mexico, residing at Calle Independencia No. 17, Mexico city, Mexico, have 5 invented certain new and useful Improvements in Processes of Sterilizing Liquids, of which the following is a specification.

The present invention relates to the sterilization of liquids, for example drinking 10 water, through the medium of an electric current passed through such liquid. By the particular novel procedure set forth in detail hereinafter, I form the liquid to be sterilized into a thin flowing film through 15 which a current of relatively low voltage and comparatively high amperage is passed in a direction transverse to the main direction of the liquid current, the electrodes being of such a nature as to avoid their 20 being affected by the liquid or by electrolytic action.

The process will be described in detail hereinafter, and defined, as to its novel features, in the appended claims.

25 The accompanying drawings illustrate, as examples, three forms of apparatus suitable for carrying out my improved sterilizing process. Figures 1 and 2 are vertical sections, on lines 1—1 and 2—2 respectively of 30 Fig. 3, showing one form of such apparatus; Figs. 3 and 4 are horizontal sections on lines 3—3 and 4—4 respectively of Figs. 1 and 2 respectively; Fig. 5 is a top view of the bottom head or plug employed in this form 35 of the apparatus; Fig. 6 is a vertical central section through another form of the apparatus, in a plane corresponding to that of Fig. 2; Fig. 7 is a cross section on line 7—7 of Fig. 6; and Fig. 8 is a similar cross section of a third form of apparatus.

The apparatus shown in Figs. 1 to 5 inclusive comprises a bottom casing A, say of circular cross section, made with an inlet 45 A' which may be screw-threaded as shown for convenient connection with the threaded end of a liquid-supply pipe (not shown), which pipe would be provided with a cock or valve to regulate or shut off the flow of liquid. An upright shell B has its lower 50 edge seated on a circumferential internal shoulder A'' of the casing A, the inner sur-

face of said shell (if the shell is made of metal) being coated or lined, as at B', with enamel, porcelain or other material which will protect the shell from oxidation, which 55 might be caused by chemical or electrolytic action if the water or other liquid were allowed to come in contact with the metal surface of the shell. The lower end of the shell receives a lower head or plug C, 60 formed with spaced segmental extensions C' engaging the inner surface of the shell lining B', while the intervening portions of said head are out of contact with the shell lining B', so as to leave two segmental passages, see D, D' in Figs. 3 and 5, in permanent communication with a chamber A* formed in the casing A below the head or plug C. At the top the shell B receives an upper head or plug E, similar to the head 65 C, but having its entire circumference in engagement with the inner surface of the shell lining B'. Each of these heads is made with a central aperture through which passes a longitudinal rod F threaded at its ends 70 to receive nuts G, G' fitted into suitable recesses in the outer faces of said heads, the latter being connected by said rod and nuts. The nuts are preferably made of insulating material, or at least of non-metallic 75 material, and with closed outer ends, to keep the liquid from contact with the metal rod F. The upper end of the shell B is connected with a ring H, secured, as by screws J, to a cap K provided with an outlet K', 80 which may be connected with any suitable means for carrying away the sterilized liquid; in Figs. 1, 2 and 4 this means consists of a glass outlet pipe L fitted into a rubber bushing L' inserted into the outlet K'. The 85 ring H and the cap K together form an upper casing corresponding to the lower casing A. The inner or lower surface of the cap K is provided with a lining K'' of enamel or other suitable material, to keep 90 the water from contact with the cap, in case the latter is made of metal which might be injured by chemical or electrolytic action if allowed to come in contact with the water. The screws J also serve to hold in place, an 100 additional cap or cover M, of insulating material, forming with the cap K a chamber N.

Between the two heads C, E, which are made of insulating material, are located the two electrodes O, O', which are alike in shape, each of them comprising two cylinder 5 segments of different diameters connected by a bend lying substantially in an axial plane, said segments being co-axial with the shell B. Preferably, each electrode comprises a core O'', made say of a copper plate, 10 and embedded in a body of carbon or like conducting material indifferent to the action of the electric current and of the water or other liquid to be sterilized. This body of pressed carbon or the like may be 15 molded on to the copper core and forms a lining on both sides thereof, as well as at the vertical edges, and even the horizontal upper and lower edges of the electrodes may be covered by such lining, as shown. The 20 said upper and lower edges of the electrodes are fitted into corresponding grooves in the opposing surfaces of the heads C, E, and the large-diameter portion of one electrode is placed adjacent to the small-diameter portion of the other electrode, so that 25 these portions will be parallel and very close together. The spacing of the overlapping electrode portions is uniform at all points of the electrodes. At the center of the apparatus 30 is located a cylindrical heat-retaining body P of carbon or other suitable material, held between the heads C, E by the rod F, which passes through a central perforation of said body. The base and the reduced upper end P' of the heat-retaining body P fit into suitable central recesses in 35 the opposing faces of the heads C, E. An annular chamber Q is formed around said reduced portion P', and this chamber communicates at every point of its periphery, 40 with the annular chamber R in which the electrodes O, O' are located, it being understood that said electrodes are spaced from the body P so as to leave an annular space 45 or passage between said body and the electrodes. Through apertures E' in the head E, the chamber Q communicates with an outlet chamber S formed between the head E and the cap K. As stated above, the two 50 cylinder segments of the same electrode are connected by radial bends, and the bends of the two electrodes are substantially in diametrical alignment, see Figs. 3 and 5; at these bends, the upper edges of the electrodes 55 are provided with projections O* passing through the head E and threaded to receive nuts T. These nuts engage washers U, and where these projections O* extend through the cap K (generally made of 60 metal), they are surrounded by insulating sleeves U', which might be made integral with the (insulating) washers U. The wires V for supplying the current pass through a suitable aperture in the cap or cover M, and

their ends are clamped against the nuts T 65 by binding nuts W of well-known character, these terminals being contained in the chamber N, and protected by the cap M.

In operation, the electrodes are connected with a source of electricity furnishing a galvanic current, that is to say, a current of relatively low voltage and comparatively high amperage, for example, five volts and 50 amperes. The water or other liquid, having been turned on, passes through the inlet A' into 70 the chamber A*, and from there through the segmental passages D, D' into the outer portion of the annular chamber R, adjacent to the shell B. The liquid will then flow first in contact with the outer surfaces of the 75 outer or large-diameter electrode segments, to reach upright slots X formed between the vertical edge of the outer segment of one electrode and the bend of the other electrode. The water or other liquid then enters the space between the two electrodes O, 80 O', and forms a film of uniform thickness engaged on opposite faces by the electrodes, said film completing the circuit; that is to say, the circuit remains open until the liquid is in contact with both electrodes. The flow of the liquid is substantially in a spiral or helical path, being partly circumferential as indicated by the arrows, and partly longitudinal (upward, toward the outlet). When 85 the liquid reaches the free edges of the inner electrode segments, it will pass inwardly through upright slots Y formed between said free edges and the bends of the other electrodes. The liquid thus reaches the annular space between the inner electrode segments and the heat-retaining body P, and from this portion of the chamber R the liquid enters the chamber Q adjacent to the head E, and from there passes through the 90 apertures E' to the chamber S and the outlet pipe L. The current passing through the liquid exerts a heating and sterilizing action thereon, and the water or other liquid is also heated by the heat produced in 95 the electrodes by the passage of the current and then transferred to the liquid; a certain portion of this electrode heat may be transferred to the liquid even before it reaches the film space between the electrodes. 100 It will be noted that in the operation described the cool water is in contact with the inner lining B' of the shell B, while the warmer water or liquid is nearer the center or axis of the apparatus; I thus practically prevent 105 the loss of heat which might be due to radiation from the shell. Obviously, the temperature to which the liquid is heated, and also the sterilizing effect of the current, will depend on the time such liquid remains in 110 the apparatus, and this is controlled by opening more or less the cock in the liquid-supply pipe leading to the inlet A'. As the 115

electrodes are very close to each other, and spaced uniformly, a very even and efficient heating and sterilizing action is obtained, and any whirling of the liquid in the space 5 between the electrodes is obviated. The electrodes are of course of different potential at the time the current passes through the liquid between them. By providing the shell B and the cap K with the protective 10 linings B' and K' respectively, I prevent the injury which might result to said parts, if made of metal, either by electrolysis or by a chemical action of the liquid. Similarly, as the electrode surfaces in contact 15 with the liquid are indifferent (non-metallic) the electrodes, and especially their cores O', are protected against oxidation and electrolytic damage. Part of the heat developed in the apparatus will be absorbed by 20 the heat-retaining body P, which thus becomes a heat-reservoir to equalize, or compensate for, any fluctuations in the heating and sterilizing effect which may be due to 25 irregularities in the flow of the liquid or of the current.

If the supply of liquid is stopped, as by closing the cock in the supply-pipe, the effect will be at first a moderate rise of the amperage, due to the fact that the 30 liquid, now become stationary, is heated to a higher temperature, at which its conductivity is greater; this period of increased amperage is however very brief (generally a few seconds), and then follows a 35 period of reduced amperage owing to the fact that the resistance is increasing progressively as the wetted surface area of the electrodes is diminished by the evaporation of the liquid. With the increase of resistance, the heating effect will finally become 40 sufficient to cause the liquid to boil or evaporate, and when the entire amount of liquid in contact with the electrodes has evaporated, there will be no electrical connection between the electrodes, and the circuit will thus 45 be broken automatically. The steam or vapor produced after the supply of liquid has been shut off, will also travel to the outlet in a spiral path. Generally, the heating 50 effect will be so adjusted as to discharge a liquid at the outlet L; in special cases, however, it might be desired to obtain a sterilized vapor or steam, and a proper regulation of the liquid-supply cock will adjust 55 conditions to secure this result, that is to say, if the cock is opened slightly, liquid may be admitted continuously through the inlet A' while steam or vapor is discharged continuously at the outlet L. The steam or 60 vapor, whether produced during the continuous admission of liquid or after shutting off the supply, will travel in a spiral path, as does the liquid at the time it flows between the electrodes.

In the construction illustrated by Figs. 65 6 and 7, which is adapted for operation by a three-phase current, there are three electrodes O², O³, O⁴, each of the general step-like arrangement described in connection with the electrodes O, O', and also made, 70 say of a carbon body pressed on and around a copper core. Each of the electrodes O², O³, O⁴, instead of comprising only two segments of different diameters, has three segments of this character, with intervening 75 bends, and placed so as to form three sets of upright slots X, Y, Z, the three slots of the same set being evenly spaced circumferentially (120° apart), and the outer segment 80 of one electrode overlapping the intermediate segment of the next electrode, which intermediate segment again overlaps the inner segment of the third electrode. All these segments are concentric with the axis of the rod F. There are three terminals or 85 binding posts, one for each of the electrodes. In other respects the construction shown in Figs. 6 and 7, and its operation, are the same as described with reference to Figs. 1 to 5.

In Fig. 8 the shell B'' (with its inner lining B'') is rectangular instead of cylindrical, and the electrodes O⁵, O⁶ are given a corresponding shape. They have inert liquid-engaging surfaces, as before (say carbon on a copper core), and consist of portions of a segmental nature arranged to overlap and to form a spiral path for the thin film of liquid traveling between the electrodes, the opposing, film-engaging faces of the electrodes being evenly spaced at all 90 points of the film, in each form of the apparatus, and the electric current passing through the film transversely, that is to say, across the film. In other respects, the construction shown in Fig. 8 may agree with 95 those first described, and its operation will be substantially the same as in Figs. 1 to 5.

Various modifications may be made without departing from the nature of my invention as set forth in the appended claims. 100

After the water has been sterilized as described, impurities contained therein may be removed in any suitable manner, say by attaching a filter to the outlet tube L, and compelling the water to pass through such 105 filter.

I claim as my invention:

1. The process of sterilizing an electrically-conducting liquid, which consists in passing the liquid, in the form of a film of 110 uniform thickness, in a spiral path, between inert electrodes, and causing a galvanic electric current (of relatively low voltage and comparatively high amperage) to flow across said film between the electrodes engaging 115 the opposite surfaces of the spirally-moving film.

2. The process which consists in passing

a galvanic current across a thin film of conducting liquid traveling spirally between inert electrodes, the stopping the flow of the liquid and continuing to pass said galvanic current through the liquid while the latter is stationary, to raise the temperature of the liquid, and removing the resulting vapors in a spiral path.

3. The process which consists in passing

a galvanic current across a spirally-moving film of a conducting liquid while absorbing part of the generated heat in a heat-retaining body in contact with said liquid, to compensate for variations in the galvanic current or in the flow of the liquid.

In testimony whereof I affix my signature.

LUIS G. ABOGADO.
